(57) **CLAIM**

The ornamental design for a fastener for a cable box, as shown and described.

DESCRIPTION

FIG. 1 is a front, perspective view of a fastener for a cable box showing my new design.

FIG. 2 is an enlarged front perspective view thereof; and, FIG. 3 is an enlarged rear perspective view thereof.

The views of FIGS. 1-3 are shown in fragmented form for ease of illustration and to indicate indeterminate length.

1 Claim, 3 Drawing Sheets

FIG. 2

FIG. 3
